[57] **CLAIM**

The ornamental design for handle for a container, as shown and described.

DESCRIPTION

FIG. 1 is a side view of the handle for a container, the opposite side being a mirror image, and the container being shown in phantom;

FIG. 2 is a rear view thereof;

FIG. 3 is an enlarged side view of the handle of FIG. 1 without the container, the opposite side view being a mirror image;

FIG. 4 is an enlarged front view thereof;

FIG. 5 is an enlarged rear view thereof;

FIG. 6 is an enlarged top view thereof; and,

FIG. 7 is an enlarged bottom view thereof.

The broken line container shown in FIGS. 1 and 2 is for illustrative purposes only and forms no part of the claimed design.
